(57) **CLAIM**

The ornamental design for a tablet, as shown and described.

DESCRIPTION

The file of this patent contains at least one drawing executed in color. Copies of this patent with color drawings will be provided by the Office upon request and payment of the necessary fee.

FIG. 1 is a top view of a first embodiment of a tablet according to the new design;

FIG. 2 is a bottom view thereof;

FIG. 3 is a front side view thereof;

FIG. 4 is a back side view thereof;

FIG. 5 is a left side view thereof;

FIG. 6 is a right side view thereof; and

FIG. 7 is a front perspective view thereof.

FIG. 8 is a top view of a second embodiment of a tablet according to the new design and having a light violet shade;

FIG. 9 is a bottom view thereof;

FIG. 10 is a front side view thereof;

FIG. 11 is a back side view thereof;

FIG. 12 is a left side view thereof;

FIG. 13 is a right side view thereof; and

FIG. 14 is a front perspective view thereof.

FIG. 15 is a top view of a third embodiment of a tablet according to the new design and having a purple grey shade;

FIG. 16 is a bottom view thereof;

FIG. 17 is a front side view thereof;

FIG. 18 is a back side view thereof;

FIG. 19 is a left side view thereof;

FIG. 20 is a right side view thereof; and,

FIG. 21 is a front perspective view thereof.

The first embodiment (FIGS. 1-7) may optionally appear white in color having RGB values of R245, G243, and B238.

The second embodiment (FIGS. 8-14) having a light violet shade may optionally have RGB values of R214, G194, and B190. The third embodiment (FIGS. 15-21) having a purple grey shade may optionally have RGB values of R187, G158, and B153.
